UNITED STATES PATENT OFFICE.

LEONARD L. FERGUSON, OF CHICAGO, ILLINOIS, ASSIGNOR TO DUNTLEY PNEUMATIC SWEeper CO., A CORPORATION OF ILLINOIS.

DESIGN FOR A CARPET-SWEeper BODY.

46,800.

Specification for Design.

Patented Dec. 29, 1914.

Application filed March 21, 1914. Serial No. 826,425. Term of patent 7 years.

To all whom it may concern:

Be it known that I, LEONARD L. FERGUSON, a citizen of the United States of America, and a resident of Chicago, in the county of Cook and State of Illinois, have invented a new, original, and ornamental Design for Carpet-Sweeper Bodies, of which the following is a specification, reference being had to the accompanying drawing, forming part thereof.

The figure is a perspective view of a carpet sweeper body showing my new design.

I claim:

The ornamental design for a carpet sweeper body as shown.

LEONARD L. FERGUSON.

Witnesses:

EUGENE A. RUMMLER,
WILLIAM E. HANN.
